UNITED STATES PATENT OFFICE.

KARL SCHIEDER, OF NUERMBERG, GERMANY, ASSIGNOR, BY MESNE ASSIGNMENTS, TO STANDARD DEVICES, INC., OF NEW YORK, N. Y., A CORPORATION OF DELAWARE.

POCKET CIGAR LIGHTER.

Application filed October 26, 1927. Serial No. 228,754.

My invention relates to pocket cigar lighters; that is, to devices to be carried in the pocket and used for conveniently and quickly lighting cigars, cigarettes and the like.

5 This application is closely associated with another application I have pending, Serial No. 210,491, filed August 4th, 1927.

I seek to give the various parts of my improved pocket cigar lighter such form and 10 arrangement as to present a number of advantages, among which are the following:

First, the casing, though in this instance made up in pieces, is rigid throughout in the sense that, for purposes of operating the 15 lighter, no part of the casing need be movable relatively to any other part thereof, the opening and closing of the casing being effected by a door, housed within the casing and having in this instance the form of a 20 barrel, slidably mounted.

Second, the fuel tank, carried by and practically forming a part of the casing, is of such form as to provide a maximum of space to be occupied by the fuel, and at the same 25 time to define and partially circumscribe another space within the casing, of suitable form and size to be occupied by the main working parts, grouped closely together.

Third, to actuate the sliding barrel and 30 the ignition mechanism by means of a single thrust rod used for the purpose, this thrust rod extending directly through a portion of the fuel tank, and yet completely separated from the fuel by means of a tube in which 35 the thrust rod is slidably mounted, the thrust rod and tube having such form that the movements of the thrust rod during the operation of the device cause a circulation of air through the tube.

40 Reference is made to the accompanying drawing forming a part of this specification, and in which like reference characters indicate like parts throughout all of the figures.

Figure 1 is a substantially central section 45 taken longitudinally through my improved cigar lighter, showing the movable parts in the positions they respectively occupy while the lighting mechanism is not in action.

Figure 2 is a section like Figure 1, but 50 showing the movable parts as they appear while the lighting mechanism is in action.

Figure 3 is a section on the line 3—3 of Figure 1, looking in the direction indicated by the arrows.

Figure 4 is a cross section through one 55 form of thrust rod, and the tube through which said thrust rod extends.

Figure 5 is a cross section through another form of thrust rod, and the tube 60 through which it extends.

A casing is shown as 6, and has the form of a small flat box, made of sheet material, preferably metal, and adapted to be carried 65 in the pocket.

The casing is provided with end caps 7 and 8, and with an opening 9 having the form of 70 a slot.

Located within the casing 6 is a partition wall 10 extending crosswise thereof, and provided with a portion 11 extending lengthwise 75 of the casing, and with another portion 12 extending crosswise of the casing. Thus the partition wall as a whole is bent as indicated in Figures 1 and 2, and has a step formation.

Upon one side of the partition wall is a 80 compartment 13, for containing fuel, this compartment being provided with a rather narrow portion 13^a, projecting away from the main portion 13.

Thus the compartment 13, with its extending portion 13^a, is essentially a fuel space 85 bounded in part by the partition wall 10 with its extending portion 11; these parts, together with the adjacent portions of the casing, constituting a fuel tank of the form indicated.

Within the casing, and upon the side of the partition wall opposite the fuel compartment just described, is another compartment 14, in form suitable for a number of working 90 parts to be contained therein and grouped closely together, as may be understood from Figures 1 and 2. The compartment 14 is thus bounded upon two of its sides by the fuel tank.

This arrangement of the compartments within the casing effects a saving of space, in the sense that most of the working parts are grouped together practically in one corner of the casing, and the fuel tank is partially fitted around the group of working parts.

The casing is provided with a screw plug 15, extending through the end cap 7, and detachably fitted into position, in order to 100 permit the introduction of liquid fuel into the fuel tank.

Carried by the partition wall 10 and ex-

tending therefrom toward the slot 9 is a rather short burner tube 16, and a wick 17 extends through the burner tube 16. This wick is for the most part contained within the fuel tank, but is provided with an exposed end portion 18 projecting into the slot 9 and adapted to be lighted, and when thus lighted there is a flame 19 within the slot 9 and reaching outwardly therefrom, as indicated in Figure 2.

Slidably mounted within the casing, and adapted to open and close the slot 9, is a barrel 20 provided with an opening 21. This barrel, when moved to the limit of its travel 15 to the left according to Figure 1, fits over the burner tube 16 and therewith completely incloses the exposed portion 18 of the wick, and extinguishes the flame 19 if such flame be present. This barrel 20 conserves the fuel 20 by preventing undue evaporation thereof, and leaves the exposed end portion 18 of the wick well saturated with the fuel and ready to be lighted.

Housed within the casing, and engaging 25 the barrel 20 and the end cap 8, is a compression spring 22 for moving the barrel 20 in one direction of its travel; that is, to the left according to Figures 1 and 2.

Connected with the barrel 20 is a thrust 30 rod 23, provided with a thumb button 24 and extending through a tube 25, the thrust rod 22 having a cross section of triangular form, as indicated in Figure 4. The thrust rod fits neatly within the tube 25, in the sense 35 that it makes a neat working fit therein; and yet owing to the angular form of the thrust rod, a little air can circulate freely through the tube 25 whenever the thrust rod is moved in the direction of its length.

40 In this connection it will be noted that a movement of the barrel 20, and particularly a rapid movement thereof, has more or less tendency to stir the little volume of air always present in the compartment 14, and 45 this causes a little circulation of air to take place through the tube 25. Again, the movement of the thrust rod, acting more or less like a piston, causes a displacement of air within the compartment 14 and still further increases the circulation of air through the tube 25.

The tube 25 is connected with the end cap 7 and extends therefrom to the partition wall 10, the connection of the tube with the two 55 parts just mentioned being liquid-tight, so that there can be no leakage of the liquid fuel into the tube 25.

60 Mounted rigidly upon the barrel 20 is a toothed rack bar 26 which engages a toothed gear wheel 27, mounted loosely upon the fixed shaft 28. Revolvably mounted upon the shaft 28 is a friction wheel 29, of the type well known in this art for producing sparks.

65 In order to enable movements of the gear wheel 27 to actuate the friction wheel 19,

I provide the gear wheel with a pawl 30, and provide a spring washer 31 for forcing the friction wheel 29 toward and against the gear wheel. This arrangement enables the rocking movements of the gear wheel 30 to 70 turn the friction wheel 29 step by step; and also prevents backward rotation of the friction wheel.

Engaging the friction wheel 29 is a flint 32, extending from and supported by a tube 75 33, this tube extending entirely through the adjacent portion of the fuel tank and thus through the body of the fuel. Within the tube 33 is a spring 34 engaging the flint 32, and an adjusting screw 35 extends into the 80 tube 33 and engages the spring 34. The operator by adjusting the screw 35 can control the pressure of the spring 34 upon the flint 32, and by so doing can control the pressure of the flint 32 against the friction wheel 29. 85

In some instances I prefer to give the thrust rod a square form in cross section, as indicated at 36, in Figure 5. For all practical purposes the action of this thrust rod is like that of the thrust rod 23 above described. 90

Whenever the operator places his thumb upon the thumb button 24 and forces the thrust rod 23 (or 36) to the right according to Figure 1, the barrel 20 uncovers the slot 9 and thus leaves the latter open. At the same time the end portion 18 of the wick is exposed, and the friction wheel 29 is actuated and grinds rapidly against the flint 32, thus producing sparks and projecting 100 them out through the slot 9 and against the exposed end portion 18 of the wick 18, producing the flame 19. Upon relaxing the pressure upon the thumb button 24 the barrel 20, under pressure of the spring 32, 105 moves to the left to the limit of its travel according to Figure 1, thus closing the slot and resuming its normal position, the flame being thereby extinguished.

This pocket cigar lighter may be constructed quite small in size, readily carried in a small pocket, and in practice operated by only one hand. 110

The operation of my device may be readily understood from the foregoing description. 115

Suppose the various movable parts occupy the respective positions indicated for them in Figure 1. The device is now in its normal condition of inactivity, and may be 120 placed in the pocket.

The operator, in order to strike a light, manipulates the device with one hand only if he cares to do so. He places his thumb against the thumb button 24, and by sudden pressure thereon moves the thrust rod quickly to the limit of its travel, to the right according to Figure 1, the various movable parts thus momentarily assuming the various abnormal positions indicated for them 125 130

in Figure 2, and the flame 19 being produced, as above described.

I do not limit myself to the precise mechanism shown, as variations may be made 5 therein without departing from my invention, the scope of which is commensurate with my claims.

Having thus described my invention, what I claim as new and desire to secure by Letters Patent is as follows:

1. A pocket cigar lighter, comprising a casing provided with a slot, a movable member carried by said casing and slideable relatively thereto for opening and closing said slot, ignition mechanism carried by said casing and disposed adjacent said slot for producing a flame therein, said ignition mechanism being connected with said movable member, a tube carried by said casing, and 15 a thrust rod connected with said movable member and extending through said tube, said thrust rod being movable longitudinally in the direction of its travel, for actuating said movable member and said ignition mechanism.

2. A device of the character described comprising a casing, a partition wall carried by said casing and so disposed as to divide the space therein into two compart-

ments, one for holding a liquid fuel, ignition mechanism located within the other of said compartments, a thrust rod extending through the compartment for holding said liquid fuel and connected directly with said ignition mechanism for the purpose of enabling the operator to operate said ignition mechanism by moving said thrust rod in the direction of its length and a tube carried by said casing and encircling said thrust rod, for enabling said thrust rod to move freely 40 back and forth without engagement with the fuel.

3. In a pocket cigar lighter the combination of a casing, ignition mechanism carried by said casing for producing a flame, 45 a thrust rod connected with said ignition mechanism and controllable by hand for actuating said ignition mechanism, and a tube extending through said casing and encircling said thrust rod, said thrust rod being so 50 fitted into said tube that by movement of said thrust rod relatively to said tube, air is caused to circulate through said tube so as to reach said ignition mechanism.

Signed at Munich, Germany, this 8th day 55 of October, 1927.

KARL SCHIEDER.
